UNITED STATES PATENT OFFICE.

JOHN P. STEPP, OF COLLEGE POINT, ASSIGNOR, BY MESNE ASSIGNMENTS, TO
THE ANSONIA RUBBER COMPANY, OF NEW YORK, N. Y.

DESIGN FOR A DRESSING-COMB.

SPECIFICATION forming part of Design No. 13,436, dated November 14, 1882.

Application filed September 9, 1880. Term of patent 7 years.

To all whom it may concern:

Be it known that I, JOHN P. STEPP, a citizen of the United States, residing at College Point, in the county of Queens and State of New York, have invented a Design for Dressing-Combs, of which the following is a specification.

In the accompanying drawings, Figure 1 is a side view of my newly-designed comb, and Fig. 2 a back view of the same.

The novel feature of my design consists of a rib or enlargement extending from end to end of the back of the comb, and formed with a series of oblique encircling grooved ribs. The teeth A A of the comb may be of usual form. The back rib or enlargement to which my design relates is shown at B. This longitudinal rib or enlargement is formed with a number

of circumferential grooves, C C C, extending around it, and terminating at the surface of the body of the comb on each side, the said grooves being flanked or bounded on each side by circumferential ribs D D, extending beyond the ordinary contour of the comb-back, the whole longitudinal rib simulating a tapering stem of bamboo formed with projections E at the ends.

Having thus described my design, what I claim as new therein, and desire to secure by Letters Patent, is—

The design for a dressing-comb, substantially as shown and described.

JOHN P. STEPP.
